UNITED STATES PATENT OFFICE.

EUGENE RILEY EDSON AND BENJAMIN F. SILLIMAN, OF CLEVELAND, OHIO,
ASSIGNORS TO THE EDSON REDUCTION MACHINERY COMPANY, OF AUGUSTA, MAINE, A CORPORATION OF MAINE.

DRIER.

SPECIFICATION forming part of Letters Patent No. 744,180, dated November 17, 1903.

Application filed April 17, 1903. Serial No. 153,066. (No model.)

To all whom it may concern:

Be it known that we, EUGENE RILEY EDSON and BENJAMIN F. SILLIMAN, citizens of the United States of America, residing at Cleveland, in the county of Cuyahoga and State of Ohio, have invented certain new and useful Improvements in Driers; and we do hereby declare the following to be a full, clear, and exact description of the invention, such as will enable others skilled in the art to which it pertains to make and use the same.

This invention relates to improvements in driers, and pertains more especially to a drier comprising a sectional jacketed interiorly-chambered horizontally-arranged cylinder, which forms the drying-chamber of the drier and is closed at its ends by suitably-applied heads.

One object of this invention is to render the drier long-lived and to construct a drier comprising corresponding interchangeable and separable jacketed annular cylinder-sections assembled endwise between the heads of the drier.

Another object is to provide each annular cylinder-section with a heating-jacket and to form the said cylinder-section by an inner annular cast-iron shell provided at each end and externally with a laterally and outwardly projecting annular flange and having two horizontal flanges arranged at opposite sides, respectively, of the said shell and formed upon and externally of the said shell centrally between the top and bottom of the shell and connecting together the end flanges of the shell, with the jacket of the said cylinder-section made in two semicylindrical sections embracing the upper portion and lower portion, respectively, of the aforesaid shell and flanged exteriorly along and secured to the aforesaid exterior flanges of the said cylinder-section and with communication between the interior chambers of the jackets of the cylinder-sections suitably established.

Another object of this invention is to render the construction simple and convenient in the assemblage and renewal of parts.

With these objects in view and to the end of realizing other advantages hereinafter appearing this invention consists in certain

features of construction and combinations of parts hereinafter described, and pointed out in the claims.

In the accompanying drawings Figure 1 is a side elevation, largely in central section, 55 of a drier embodying the invention which constitutes the subject-matter of this application.

Our improved drier comprises an interiorly-chambered jacketed cylinder composed of 60 annular sections *a*, assembled endwise and horizontally arranged in line between two heads *b*, which close opposite ends, respectively, of the drying-chamber formed by and interiorly of the said cylinder-sections. The 65 cylinder of the drier illustrated is therefore arranged horizontally and comprises three annular sections *a*. Each cylinder-section *a* comprises an inner cylindrical cast-iron shell *c*, exteriorly jacketed, as will herein- 70 after appear. Each shell *c* is provided at each end and externally with a laterally and outwardly projecting annular flange *d*. Each shell *c* is provided exteriorly and at each side centrally between the top and bottom 75 of the said shell with a horizontally-arranged flange *e*, which extends longitudinally of the shell and connects together and braces apart the annular end flanges *d* of the shell. Each cylinder-section *a* comprises also a 80 heating-jacket, which comprises two plate-metal semicylindrical sections *f*, which embrace the upper portion and lower portion, respectively, of the shell *c* of the said cylinder-section *a*.

The upper jacket-section *f* of each cylinder-section *a* embraces and conforms to the upper portion of the shell *c* of the said cylinder-section and rests at the bottom upon the flanges *e* of the said cylinder-section, and the 90 said jacket-section *f* is provided at the upper sides of the said flanges *e* and exteriorly with laterally and outwardly projecting horizontally-arranged flanges *g*, which abut against the upper sides of and extend longitudinally 95 of the said flanges *e*.

The lower jacket-section *f* of each cylinder-section *a* embraces and conforms to the lower portion of the shell *c* of the said cylinder-section and is arranged below the flanges *e* of 100

the said shell. The said lower jacket-section is provided next below each flange *e* of the said shell with a laterally and outwardly projecting horizontally-arranged flange *h*, which 5 abuts against the under side of the said flange *e* of the said shell.

The flanges *g* and *h* of the jacket-sections *f* of each cylinder-section *a* are riveted, as at *k*, to the flanges *e* of the shell *c* of the said 10 cylinder-section.

Each jacket-section *f* of each cylinder-section *a* extends snugly between the end flanges *d* of the shell *c* of the said cylinder-section and is provided at the ends with laterally and 15 outwardly projecting flanges *l*, which abut against and extend along the said flanges *d* of the said shell and are riveted to the last-mentioned flanges, as at *m*. Each jacket-section *f* is enough larger than the adjacent portion 20 of the shell *c* embraced by the said jacket-section to form a chamber *n* between the said jacket-section and the said shell *c*, and communication between the two chambers *n*, formed next exteriorly of the upper 25 portion and lower portion, respectively, of the said shell *c* by the jacket-sections *f*, embracing the said shell, is established by holes or ports *p*, formed in and extending vertically through the flanges *e* of the said shell between 30 the latter and the said jacket-sections and arranged at suitable intervals longitudinally of the said flanges. Communication between the chambers *n* of adjacent cylinder-sections *a* is established by slots or ports *r*, 35 formed in and extending laterally through the adjacent end flanges *d* of the said sections at suitable intervals circumferentially of the said sections and next to the inner sides of the jacket-sections *f* of the said cylinder-sections. 40

As already indicated, the cylinder-sections *a* correspond in dimensions and construction, so that they are interchangeable, and adjacent sections *a* are separably secured together by suitably-applied bolts and nuts. 45 Adjacent flanges *d* of adjacent cylinder-sections *a* beyond the outer sides of the jacket-sections *f* of the said cylinder-sections have registering horizontally-arranged holes *s* extending therethrough at suitable intervals circumferentially of the said cylinder-sections and engaged by bolts *t*, and correspondingly-threaded nuts *u* are mounted upon the screw-threaded shanks of the said bolts, and 50 the arrangement of the parts is such that the said cylinder-sections *a* have their said flanges clamped together by and between each bolt *t* and the nut *u* upon the said bolt. It will be observed, therefore, that adjacent cylinder-sections *a* are separably clamped together. 55

The shell *c* of each cylinder-section *a* is provided with a pipe connection *w*, arranged centrally between the ends of the said shell and centrally between the flanges *e* of the said shell, which pipe connection has its interior 60 passage-way communicating with the interior chamber of the said shell and extends through

the adjacent jacket-section *f* of the said cylinder-section, which jacket-section is suitably apertured, as at *x*, to accommodate the location of the said pipe connection and secured to the said shell at suitable intervals around the said pipe connection by screws *y*. 70

As already indicated, one of the jacket-sections *f* of each cylinder-section *a* surrounds the pipe connection *w* of the said cylinder-section, whereas the other jacket-section *f* of the said cylinder-section is provided diametrically opposite the aforesaid pipe connection *w* with a comparatively diametrically smaller 80 pipe connection *v*, whose interior passage-way communicates with the chamber *n*, formed next interiorly of the last-mentioned jacket-section.

By the construction hereinbefore described 85 it will be observed that upon loosening the nuts *u* instrumental in clamping adjacent cylinder-sections *a* together each of the said sections is rendered free to be turned independently of the other of the said sections, 90 and hence the cylinder-sections are adjustable circumferentially.

In Fig. 1 the arrangement of the parts is such that the pipe connections *w* of the outer cylinder-sections *a* are at the top of the drier and the pipe connections *v* of the jackets of the said cylinder-sections are at the bottom, whereas the pipe connection *w* of the central cylinder-section *a* is at the bottom and the pipe connection *v* of the jacket of the last-mentioned cylinder-section is at the top. Consequently in the drier illustrated the pipe connection *w* of the central cylinder-section *a* forms the material-discharging outlet of the drying-chamber of the drier, through which 100 outlet material is removed from within the said chamber, whereas the pipe connection *w* of each outer cylinder-section *a* forms a charging-aperture and vapor-outlet, through which the said chamber is supplied with material to 105 be dried or heated within the said chamber and which accommodates the escape of vapors and gases from the said chamber. It will be observed also that the pipe connection *v* of the central cylinder-section *a* in Fig. 1 forms 110 the steam-inlet of the jacket of the drier, whereas the pipe connections *v* of the outer cylinder-sections *a* constitute the drain passage-ways of the said jacket. 115

The upper portions of the shells *c* of the cylinder-sections *a* because of their greater exposure to iron-corroding vapors and gases arising from material treated within the drying-chamber become worn more rapidly than the lower portions of the said shells, and consequently the importance of the circumferential adjustability of the cylinder-sections *a* is obvious. When, therefore, the upper portions of the shell *c* of the cylinder-sections *a* become worn to such an extent that a readjustment of the said sections is deemed advisable, the nuts *u* are loosened to accommodate the said readjustment, whereupon the cylinder-sections *a* are turned half-way 120 125 130

round, and then the pipe connection *w* of the central cylinder-section *a* will be the charging-aperture or vapor-outlet of the drier, the pipe connections *w* of the outer cylinder-sections *a* will form discharge passage-ways, the pipe connection *v* of the jacket of the central cylinder-section *a* will be a drain passage-way, and the pipe connections *v* of the jackets of the outer cylinder-section *a* will 5 form steam-inlets. Of course the nuts *u* are retightened upon a readjustment of the cylinder-sections *a*. By the construction hereinbefore described it is obvious also that any two cylinder-sections showing a great difference 10 in the wear of their shells *c* may be interchanged to advantage.

The ports *r* in each of the adjacent flanges *d* of adjacent cylinder-sections *a* register with the ports *r* in the other of the said flanges, 20 and the arrangement of the said ports circumferentially of the said cylinder-sections is such that communication between the lower chambers *n* of the jackets of the said cylinder-sections shall be established at the bottom and centrally of the said chambers in either adjustment of the cylinder-sections, so that any water resulting from condensation 25 of steam within the said chambers can freely pass between the said chambers.

The arrangement of the bolt-holes *s* of adjacent flanges *d* of adjacent cylinder-sections *a* is such that the holes *s* in each of the said flanges shall register with the holes *s* in the other of the said flanges in either adjustment 30 of the said cylinder-sections.

The heads *b*, which close the ends of the drying-chamber of the drier, are preferably interchangeable. Each head *b* overlaps the adjacent flange *d* of the adjacent cylinder-section *a*, and suitably-applied bolts and nuts clamp the said head to the said flange, as at B. The heads *b* are provided centrally with stuffing-boxes *G*, which surround the stirring-shaft *K*, which is arranged horizontally and extends centrally through the drier, which shaft is supported in any approved manner and is provided within the drying-chamber with radially-arranged stirring-arms *L*.

50 What we claim is—

1. A drier comprising two heads arranged a suitable distance apart laterally of each other and closing opposite ends respectively of the drying-chamber, and a cylinder forming the surrounding wall of the said chamber and comprising annular sections which are arranged in line endwise between the heads and comprise each an inner cylindrical shell provided at each end and externally with a laterally and outwardly projecting flange and having also two flanges formed upon and exteriorly of the said shell at opposite sides respectively of the shell and extending longitudinally of the shell; two jacket-forming sections embracing the upper portion and lower portion respectively of the said shell and forming chambers next exteriorly of the 55 said shell and having flanges extending longitudinally of and secured to the aforesaid longitudinally-extending flanges of the said shell which jacket-forming sections are provided at the ends with flanges extending along and secured to the end flanges of the said shell; two pipe connections arranged diametrically opposite each other and one of said pipe connections communicating with the aforesaid drying-chamber and extending through one of the said jacket-sections, and the other of said pipe connections communicating with the chamber formed by the other of said jacket-sections; means 60 separably clamping adjacent end flanges of the cylinder-shells of adjacent cylinder-sections together; means establishing communication between the chambers formed by the jacket-sections of each cylinder-section, and means establishing communication between the jacket-chambers of adjacent cylinder-sections.

70 said shell and having flanges extending longitudinally of and secured to the aforesaid longitudinally-extending flanges of the said shell, which jacket-forming sections are provided at the ends with flanges extending along and secured to the end flanges of the said shell; a pipe connection having its interior passage-way communicating with the aforesaid drying-chamber and extending through one of the said jacket-sections; a pipe connection having its interior passage-way communicating with the chamber formed by the other of the said jacket-sections, and 75 bolts and nuts separably clamping adjacent end flanges of the cylindrical shells of adjacent cylinder-sections together, and the chambers formed by the jacket-sections of each cylinder-section being in communication with each other and in open relation with the chambers formed by the jacket-sections of the adjacent cylinder-section or cylinder-sections.

2. A drier comprising two heads arranged a suitable distance apart laterally of each other and closing opposite ends respectively of the drying-chamber, and a cylinder forming the surrounding wall of the said chamber and comprising annular sections which are arranged in line endwise between the heads 90 and comprise each an inner cylindrical shell provided at each end and externally with a laterally and outwardly projecting flange and having also two flanges formed upon and exteriorly of the said shell at opposite sides respectively of the shell and extending longitudinally of the shell; two jacket-forming sections embracing the upper portion and lower portion respectively of the said shell and forming chambers next exteriorly of the 95 said shell and having flanges extending longitudinally of and secured to the aforesaid longitudinally-extending flanges of the said shell which jacket-forming sections are provided at the ends with flanges extending along and secured to the end flanges of the said shell; two pipe connections arranged diametrically opposite each other and one of said pipe connections communicating with the aforesaid drying-chamber and extending 100 through one of the said jacket-sections, and the other of said pipe connections communicating with the chamber formed by the other of said jacket-sections; means 105 establishing communication between the chambers formed by the jacket-sections of each cylinder-section, and means establishing communication between the jacket-chambers of adjacent cylinder-sections.

3. A drier comprising two heads arranged a suitable distance apart laterally of each other and closing opposite ends respectively 110 of the drying-chamber, and a cylinder forming the surrounding wall of the said chamber and comprising annular sections which are arranged in line endwise between the heads 115 and comprise each an inner cylindrical shell provided at each end and externally with a laterally and outwardly projecting flange and having also two flanges formed upon and exteriorly of the said shell and extending longitudinally of the shell; two jacket-forming sections embracing the upper portion and lower portion respectively of the said shell and forming chambers next exteriorly of the 120 said shell and having flanges extending longitudinally of and secured to the aforesaid longitudinally-extending flanges of the said shell which jacket-forming sections are provided at the ends with flanges extending along and secured to the end flanges of the said shell; two pipe connections arranged diametrically opposite each other and one of said pipe connections communicating with the aforesaid drying-chamber and extending 125 through one of the said jacket-sections, and the other of said pipe connections communicating with the chamber formed by the other of said jacket-sections; means establishing communication between the chambers formed by the jacket-sections of each cylinder-section, and means establishing communication between the jacket-chambers of adjacent cylinder-sections.

- and comprise each an inner cylindrical shell provided at each end and externally with a laterally and outwardly projecting flange, and having also two flanges formed upon and exteriorly of the said shell at opposite sides respectively of the shell and extending longitudinally of the shell; two jacket-forming sections embracing the said shell and forming chambers next exteriorly of the said shell 5 and having flanges extending longitudinally of and secured to the aforesaid longitudinally-extending flanges of the said shell, which jacket-forming sections are provided at the ends with flanges extending along and 10 secured to the end flanges of the said shell; means separably clamping adjacent end flanges of the cylindrical shells of adjacent cylinder-sections together, and the chambers formed by the jacket-sections of each cylinder-section being in communication with each other and in open relation with the chambers formed by the jacket-sections of the adjacent cylinder-section or cylinder-sections. 15
4. A drier comprising two heads arranged 25 a suitable distance apart laterally of each other and closing opposite ends respectively of the drying-chamber, and a cylinder forming the surrounding wall of the said chamber and comprising annular sections which are 30 arranged in line endwise between the heads and comprise each an inner cylindrical shell provided at each end and externally with a laterally and outwardly projecting annular flange; jacket-forming sections embracing 35 the said shell and having flanges extending along and secured to the aforesaid flanges of the said shell; means separably clamping adjacent flanges of the cylinder-shells of adjacent cylinder-sections together, and the 40 chambers formed by the jacket-sections of each cylinder-section being in communication with each other and in open relation with the chambers formed by the jacket-sections of the adjacent cylinder-section or cylinder-sections. 45
5. A drier comprising two heads arranged a suitable distance apart laterally of each other and closing opposite ends respectively of the drying-chamber, and a cylinder forming 50 the surrounding wall of the said chamber and comprising annular sections which are
- arranged in line endwise between the heads and comprise each an inner cylindrical shell provided at each end and externally with a laterally and outwardly projecting annular flange, and having also two flanges formed upon and exteriorly of the said shell at opposite sides respectively of the shell and extending longitudinally of the shell; two jacket-forming sections embracing the said shell and forming chambers next exteriorly of the said shell and having flanges extending longitudinally between and contiguous to the end flanges of the said shell and secured to the aforesaid longitudinally-extending flanges of 6; the said shell, which jacket-forming sections are provided at the ends with flanges extending along and secured to the end flanges of the said shell, and the chambers formed by the jacket-sections of each cylinder-section 70 being in communication with each other and in open relation with the chambers formed by the jacket-sections of the adjacent cylinder-section or cylinder-sections. 75
6. A drier comprising two heads arranged a suitable distance apart laterally of each other and closing opposite ends respectively of the drying-chamber, and a cylinder forming the surrounding wall of the said chamber and comprising annular sections which are 80 arranged in line endwise between the heads and comprise each an inner cylindrical shell provided at each end and externally with an annular flange and having also two horizontally-arranged flanges formed upon and exteriorly of the said shell at opposite sides respectively of the shell and extending longitudinally of the shell between and connecting together the end flanges of the shell, and two jacket-forming sections embracing the 85 upper portion and lower portion respectively of the said shell and forming chambers next exteriorly of the said shell and having flanges extending along and secured to the aforesaid flanges of the said shell. 90
